United States Patent Office

Des. 219,267
Patented Nov. 24, 1970

219,267

FASCIA

William C. Heirich, 515 S. 15th St.,
Muskogee, Okla. 74401

Continuation-in-part of design application Ser. No. 7,038,
May 9, 1967. This application Mar. 3, 1969, Ser. No.
15,982

Term of patent 14 years

Int. Cl. D25—01

U.S. Cl. D13—1

FIG. 1

FIG. 2

FIG. 5

FIG. 6

FIG. 1 is a perspective view of a first embodiment of the present invention;

FIG. 2 is a cross-sectional view of the first embodiment taken along line 2—2 of FIG. 1;

FIG. 3 is a perspective view of a second embodiment of the present invention;

FIG. 4 is a cross-sectional view of the second embodiment taken along line 4—4 of FIG. 3;

FIG. 5 is a perspective view of a third embodiment of the present invention; and

FIG. 6 is a cross-sectional view of the third embodiment taken along line 6—6 of FIG. 5.

The present application is a continuation-in-part of application Ser. No. D. 7,038 filed May 9, 1967 entitled Fascia and now abandoned.

I claim:

The ornamental design for the fascia, as shown and described.
